UNITED STATES PATENT OFFICE.

MARK E. SHERLAND, OF McGEHEE, ARKANSAS, ASSIGNOR OF ONE-HALF TO ENSLEY E. WILLIAMS, OF McGEHEE, ARKANSAS.

DRY CLOSET.

1,066,667.

Specification of Letters Patent.

Patented July 8, 1913.

Application filed August 10, 1912. Serial No. 714,425.

To all whom it may concern:

Be it known that I, MARK E. SHERLAND, a citizen of the United States, residing at McGehee, in the county of Disha and State 5 of Arkansas, have invented certain new and useful Improvements in Dry Closets, of which the following is a specification.

My invention relates to improvements in dry closets, and is designed to improve the 10 construction of closets of this character in several particulars.

The prime object of the invention is the provision of a sanitary closet that may be supplied with a disinfectant in a convenient 15 and effective manner, that may be cleansed with facility, and that is comparatively cheap in first cost and simple in construction.

The invention consists essentially in the 20 combination and arrangements of parts as hereinafter pointed out and specified in my appended claims.

In the accompanying drawings I have exemplified one complete example of the 25 physical embodiment of my invention constructed according to the best mode I have so far devised for the practical application of the principles of the invention.

Figure 1 is a front view of a closet embodying the novel features of my invention, the ventilator and disinfectant distributing 30 pipes being broken away for convenience of illustration. Fig. 2 is a transverse view in section. Fig. 3 is a vertical longitudinal sectional view, at right angles to Fig. 2, and Fig. 4 is a perspective view of one of the disinfectant trays or drawers, employed in the invention.

In the preferred embodiment of my invention I employ a trap or receptacle 1, which may be of metal, wood, or other suitable material, but in the drawings I have illustrated the receptacle as made of galvanized iron.

At its rear the receptacle is provided with a door 2, hinged at 3, and adapted to swing 45 downwardly. The rear wall of the receptacle as indicated at 4, is cut away near the bottom and exposes an opening for the insertion of a tray or flat box 5 having perforations 6 in its upper surface, which forms 50 a false floor or bottom for the receptacle.

At the ends of the rear side the wall is cut away to admit of the insertion of a pair

of trays or drawers, 7 and 8 each having its 55 inner face perforated as at 9. As clearly seen in Fig. 3 these two trays 7 and 8 may be pushed into the ends of the receptacle 1, resting on the upper face of the flat box 5 and guided by the strips 10. 60

The upper wall or top of the receptacle 1 is provided with a pair of openings, as 11 over which the duplicate sections 12 of the sectional hoppers 13 are placed. The two sections of the hoppers may be adjusted 65 with relation to each other and so held, by means of the screw bolts 14 and nuts 15 which hold the parts together through the medium of ears 16, as will be understood. If desired the upper and lower sections of 70 these hoppers may, respectively, be fastened to the underside of the box seat 17 and the top surface of the receptacle 1.

Toward the rear of the receptacle 1 and located about midway of its ends, the top of 75 the receptacle is provided with a ventilating opening over which the foraminous screen 18 is placed, and above the opening a pipe or tube 19 is placed which is passed through an opening in the box seat, and from this 80 point an upwardly extending ventilating pipe 20, with a cap 21, passes out through the top of the housing about the closet, (not shown).

The drawers, boxes or trays for the disinfectant may be filled with lime for instance, through the opening as at 22, before being placed in the receptacle. But I prefer to use the illustrated disinfectant device as shown in Fig. 1, wherein a tank 23 is provided with a series of pipes or tubes 24 extending down into the openings 22. By means of a slide or valve 25 located just below the disinfectant tank, the lime may be admitted to either or all of the conveying 90 tubes 24. 95

It will be understood that changes within the scope of my claims may be made in the installation of my invention, such for instance as changes in the number of hoppers and consequent additions of receptacles and trays, without departing from the spirit of 100 my invention.

From the above description taken in connection with the drawings it is evident that 105 I have provided a device of this character which fulfils the conditions set forth as the object of my invention.

Having thus fully described my invention, what I claim as new and desire to secure by Letters Patent is:—

1. The combination in a dry closet with a receptacle, of a removable receptacle forming a bottom and having a foraminous upper wall, independent, removable side trays each formed with a foraminous inner wall, and suitable hoppers connected to said receptacle.
2. The combination in a dry closet with a receptacle of a removable bottom receptacle

formed with an upper foraminous wall, independent, removable side trays each formed with a foraminous inner wall, hoppers connected to said receptacle, a ventilating duct, a disinfectant tank and tubes from said tank to said trays.

In testimony whereof I affix my signature in presence of two witnesses.

MARK E. SHERLAND.
